UNITED STATES PATENT OFFICE.

SAM FRIEDMAN, OF ATLANTA, GEORGIA.

HAIR-GAUGE CLIPPER.

Application filed October 19, 1923. Serial No. 669,609.

To all whom it may concern:

Be it known that I, SAM FRIEDMAN, a citizen of the United States of America, residing at Atlanta, in the county of Fulton and State of Georgia, have invented certain new and useful Improvements in Hair-Gauge Clippers, of which the following is a specification.

This invention relates to improvements in gauges for hair clippers, in the use of which the gauge may be adjusted either automatically or manually to vary the cutting depth of the clipper.

The invention is directed to a gauge comprising a member having slidable cooperation with the usual hair clipper and formed with teeth to register with the cutting teeth of the clipper to thereby provide slots through which the hair may reach the cutting teeth of the clipper. An adjusting screw is provided, having threaded connection with the gauge and detachably connected at one end with the base plate of the clipper proper, whereby in the adjustment of the gauge by means of the screw, the operative or toothed end of the latter is caused to move forwardly or rearwardly, and through its normal angular relation to the base plate of the clipper, will, in such movement, be positioned farther from or closer to the cutting teeth, thereby increasing or decreasing the length of hair cut in the normal operation of the clipper.

The invention is designed for connection with the usual hand clipper, or is designed for connection with the motor driven clipper, the adjustment of the gauge in the former case being a manual one, and the adjustment of the gauge in the latter case being an automatic one, with the control of the automatic operating means manually governed.

The invention is illustrated in the accompanying drawings, in which:

Fig. 1 is a view in bottom plan, partly in section, illustrating the application of the improved gauge to an automatically operated or power driven hair clipper.

Fig. 2 is a broken perspective showing the gauge as designed more particularly for hand operated clippers, a portion of the base plate of the clipper being shown.

Figs. 3 and 4 are sectional views illustrating different positions of the gauge relative to the cutting teeth of the clipper.

Fig. 5 is a detail sectional view showing

the connection of the operative end of the adjusting screw with the base plate of the clipper.

Fig. 6 is a side elevation of Fig. 1 illustrating particularly the relative disposition of the gauge.

Fig. 7 is a plan showing another form or gauge operating means as applied to a hand operated clipper.

The improved gauge comprises a base 1 formed at its forward end with teeth 2, preferably of materially greater depth than the cutting teeth 3 of the clipper. The outer or bearing surface of the base 1 is rounded at 4, and said base is integrally provided with side walls 5, which increase in height toward the rear of the gauge. The side walls 5 of the gauge are formed on their inner surfaces with channels 6 to receive the base plate 7 of the clipper proper. This base plate is formed with a transverse channel 8, in which the guide for the movable cutter plate is mounted, and for the purposes of the present invention, one end of this channel is utilized in providing for the adjustment of the clipper. For this purpose a circular head 9 is swiveled upon one end of an adjusting screw 10, and this head 9 is slotted at 11 so as to snugly embrace the base plate 7 of the clipper proper and fit in the channel 8 thereof. Thus the head 9 is held slidably within the slot 6 and fixed with relation to the base plate 7 of the clipper proper by cooperation with the channel 8 thereof. The clipper proper is held in this relation with the gauge by providing a leaf spring 12 in the opposite slot 6, as will be seen from Fig. 1. The adjusting screw 10 extends through a threaded socket 13 secured at the rear end of the clipper in line with the particular slot 6, the socket having an extension 14 to overlie one end of the particular wall 5 to permit of securing the socket removably in place by a screw 15.

In the form shown in Fig. 1, which indicates a power driven clipper, the power shaft 16 extends through a housing 17 having a lateral portion 18. The power shaft 16 is provided with loose pinions 19 and 20 which cooperate with a pinion 21 on a stub shaft 22 mounted in the housing extension, which stub shaft has a small pinion 23 cooperating with a large pinion 24 to drive a shaft 25 having a universal connection at 26 with the adjusting screw 10.

Mounted within the housing 17 is a double ended clutch member 27 controlled by a finger piece 28, the clutch member being formed to cooperate at will with either of the pinions 19 or 20.

Obviously by causing the power shaft 16 to operate either pinion 19 or 20 at will, the gauge adjusting screw 10 may be moved in either direction and thus cause the gauge 10 to move toward or from the cutting teeth 3 of the clipper, as will be apparent from Fig. 1, and as indicated in Figs. 3 and 4. It is of course understood that the relative sizes of the pinions 23 and 24, together with an extremely fine thread on the adjusting screw 15, causes the gauge to move slowly and thus gradually change the length of hair cut by the clipper from the start to the finish of the stroke. Obviously with the gauge at its 20 minimum distance from the teeth 3, and the cutting stroke started, the hair will be cut very short, and if the appropriate pinion 19 or 20 is then moved into cooperation with the power shaft, the movement of the gauge 25 will be started, and as the stroke continues, the length of hair left standing as the clipper moves upwardly on the head will be gradually increased. Having completed the stroke, the operator will reverse the gauge, 30 restoring it to its minimum gauge position, by shifting the clutch, and will start at the lower portion of the head for the next cut. Thus the hair will be cut of even length during the successive movements of the clipper.

35 In using the particular gauge with the ordinary hand operated clipper, the adjusting screw 10 may be provided with a knurled operating head 29, as in Fig. 2, and the gauge adjustment in this case will be carried out manually by turning the adjusting screw as desired.

40 In Fig. 7, I have shown a slight modification with respect to the operating means where the gauge is applied to a hand operated clipper. In this form, the adjusting screw 10 is mounted at its outer end in a bracket 30 secured to the gauge, the terminal of the adjusting screw being provided with a beveled pinion 31. A transverse shaft 32 is mounted in the bracket beyond the end 45 of the adjusting screw and is provided at one end with a beveled pinion 33 to cooperate with the pinion 31, and at the opposite end with an operating disc 34 having a handle 35. Thus in this form, the adjustment of the gauge may be carried out during the clipping operation in a manner approximating that of the automatic power driven mechanism.

50 It is of course to be understood that the gauge may be permanently set for any desired cutting length of the clipper, and this with either form of the construction shown, so that if it is desired that the clipper shall 55 cut a uniform distance from the skin

throughout a particular cut, as on top of the head for example, the gauge may be set to the required distance, and the clipper operated in the usual manner. The teeth 2 of the clipper serve to separate the hair and cause 70 them to be drawn in an upright position, so that the cutting teeth of the clipper may operate with greater facility. Thus the gauge serves all the functions of the comb in the ordinary hair cutting operation, as it 75 tends to straighten the hair for cutting and at the same time provide for such cutting distance as to leave any desired length of hair standing and to automatically and gradually vary this distance if such result 80 is desired.

The gauge proper may be constructed of any appropriate material, and as is obvious, may be readily removed from the clipper when it is necessary to clean or repair the 85 parts.

If desired, and as preferred, the operative surface 4 of the gauge may be provided with a roller 30 for convenience in moving the gauge over the hair in the clipping operation. 90

Claims:

1. In a clipper, a gauge having side walls formed with slots disposed at an angle to the plane of the gauge, and means operative in the gauge and having removable connection with the clipper proper to adjust the gauge relative to the clipper. 95

2. A gauge for hair clippers, comprising a base formed with comb teeth at one end, walls formed with slots at an angle to the base, an adjusting member having threaded connection with one side wall and extending lengthwise the slot, and a head mounted upon one end of the rod and adapted to interfit with a portion of the clipper with 100 which the gauge cooperates. 105

3. A gauge for hair clippers, comprising a base formed with comb teeth at one end, the bottom surface of the gauge being curved longitudinally, side walls formed with slots at an angle to the base, an adjusting screw having threaded connection with one side wall and extending lengthwise the slot, and means carried by one end of said screw to engage a clipper plate. 110 115

4. A clipper, a gauge having comb teeth at one end thereof, side walls formed with slots disposed at an angle to the plane of the gauge, a set screw having threaded connection with one side wall, and means carried by the set screw within one of the slots to interfit with a portion of the clipper proper, whereby movement of the adjusting screw causes movement of the gauge relative to the clipper. 120 125

5. A gauge for hair clippers, comprising a base formed with comb teeth at one end, side walls formed with slots at an angle to the base, an adjusting screw having threaded connection with one side wall and extending 130

lengthwise the slot, and means carried by one end of said screw to engage a clipper plate. 10

6. A gauge for hair clippers, comprising a base formed with comb teeth at one end, side walls formed with slots at an angle to the base, an adjusting screw having threaded connection with one side wall and extending lengthwise the slot, means carried by one end of said screw to engage a clipper plate, and a roller mounted in the operative surface of the base. 10

In testimony whereof I affix my signature.

SAM FRIEDMAN. [L.s.]
